UNITED STATES PATENT OFFICE.

NEWTON A. DAVIS, OF CHICAGO, ILLINOIS.

SLIDING DOOR.

No. 880,865.

Specification of Letters Patent.

Patented March 3, 1908.

Application filed June 22, 1906. Serial No. 322,914

To all whom it may concern:

Be it known that I, NEWTON A. DAVIS, citizen of the United States, residing at Chicago, in the county of Cook and State of Illinois, have invented new and useful Improvements in a Sliding Door, of which the following is a specification.

This invention relates to improvements in sliding doors and more especially to the class of doors used on express and mail cars; and has for its object to provide a door that is weather proof and can be easily opened and closed.

In the drawing, Figure 1 is an elevation looking at the inside of a car, the door being partly open. Fig. 2 is a vertical section on line 2, Fig. 1, looking in the direction indicated by the arrow; and Fig. 3 is a horizontal section on line 3, Fig. 1.

20 A may represent the body or one of the side walls of a car; B the sliding door, and C the car-doorway.

The body of the sliding door may be of the usual construction and is supported in its suspended position by means of hangers 4 and 5 rigidly secured to the door and having the grooved track or trolley rollers 6 journaled therein, as best shown in Fig. 2. An angle plate consisting of a vertical part 7 and 30 a horizontal part 8 is rigidly secured to the inside of the car, the track-rail 9 supporting the sliding movement of the door, being fastened to the horizontal part 8.

The track-rail 9 is provided with cut out notches or depressions 10, forming a low part in the track, as shown in Fig. 1. These notches consist of an incline 11 and a stop-shoulder 12. When the door is in its closed position the track rollers rest in the lowest part of the notches in the track and abut against shoulders 12, the bottom of the door resting on the sill 13 and back of a ledge 14 formed thereon. The partly open position of the door in Fig. 1, corresponds to the position in Fig. 2, that is, the trolley rollers being on the high part of the track and the bottom of the door raised up proportionately from the sill and entirely out of contact therefrom during the time that the rollers rest in the high part of the track in the opening and closing movement. When the rollers strike the incline in the track on the closing movement, the door gradually lowers until it is tightly closed at the bottom. By this arrangement it will be readily seen with what ease a sliding door may be opened and closed

without the possibility of cramping or sticking.

An angle or channel-plate 15 is rigidly fastened to the top of the door, the free-flange 16 being set away far enough from the back of the door to provide a space 17 (Fig. 2) for the loose engagement of a corresponding flange 18 of an angle-plate 19 secured to the top-part 20 of the door casing. The flanges 16 and 18 overlap each other, the flange 16 fitting loosely into the space 17 between the free flange 18 and the casing. The flanges 16 and 18 always overlap no matter whether the door is open or closed, 70 and in addition to making a weather proof closure, also lock the door against a lateral displacement at the top and the hanger rollers from running off the track. The relative position of the flanges shown in Fig. 2, corresponds to the open position of the door. When the door is closed the flange 16 drops down and nearly contacts with the horizontal part of flange 18.

The rear door post D (Fig. 3) has an angle plate 21 secured thereto. The web 22 of this plate will conform to the contour of the surface covered and has the inner edge turned at right angles to provide a free flange 23, leaving a space 24 between the same and the adjacent inner side of the door post. The corresponding edge of the door has a channel plate 25 mounted thereon. The inner side flange 26 of this plate overlaps the free flange 23 and occupies the space 24, when the door is closed, as shown in Fig. 3. The front edge of the door will close into the door-post, not shown, in the usual manner. By this arrangement it will be readily seen that a sliding door can be made substantially weather-proof and cannot be affected by atmospheric changes, and can be opened and closed with the greatest facility under all ordinary conditions.

Having thus described my invention, 100 what I claim is—

1. In a sliding door structure, the combination with the door and door casing spaced laterally from each other, and a trolley rail secured to the latter and trolley wheels to the former, of a plate extending substantially the width of the casing and having a horizontal portion underlying the under side of the upper part thereof and an upturned flange occupying the space between door and casing, and a plate extending substantially the width of the door and having a horizon-

tal portion overlying the top of the door and a depending flange overlapping the other flange and interposed between the latter and the door-casing.

5 2. In a sliding door structure, the combination with the door and door casing spaced laterally from each other, of a channel iron having one flange secured to the inner face of the rear side-post of the door-casing and the 10 other flange received freely in the space left between door and casing, and a channel iron

embracing the rear vertical edge of the door with one flange spaced from the face of the door so as to be received between such free flange and the casing, when the door is 1 closed.

In testimony whereof I affix my signature, in presence of two subscribing witnesses.

NEWTON A. DAVIS.
